UNITED STATES PATENT OFFICE.

RAY L. CARTER, OF SYRACUSE, NEW YORK.

ADJUSTABLE SUPPORT FOR ROUTING MACHINES.

Application filed February 7, 1925. Serial No. 7,727.

This invention relates to means for mounting motor driven routing and shaping machines for universal movements over the work, and has for its object to provide a 5 novel, simple and handy bracket, which is composed of several pivotally arranged sections, by which a routing machine may be supported and moved in all directions relatively to the work, the said bracket being 10 adjustably mounted upon a rigid pedestal, by which the bracket may be rotated horizontally, as well as moved vertically, for performing work at different levels and angles. A further object is to provide novel means 15 for adjustably mounting the motor, that actuates the routing and shaping tools, upon one of the sections or members of the bracket. A further object is to provide means for locking each of the sections of 20 the bracket in various adjusted positions relatively to the adjacent sections, and for locking the motor supporting section independently of the other locking means. A further object is to provide means for accurately predetermining the angles at which 25 the tools may be operated. And a further object is to provide means for adjusting the motor and tool axially independent of the bracket and the pedestal.

30 I attain these objects by the means set forth in the detailed description which follows, and as illustrated by the accompanying drawing, in which—

Figure 1 is a front side elevation of the 35 complete device; showing by full and dotted lines the adjustable nature of the bracket that supports the shaping and routing machine. Fig. 2 is a top plan view; showing by full and dotted lines a number of different positions the router, as well as the 40 bracket, may be adjusted and set for performing work at different points relatively to the pedestal. Fig. 3 is a broken side elevation, showing the motor of the full line 45 position of Fig. 1 tilted at an angle in a vertical plane. And Fig. 4 is a detached view of the swivel member of the motor supporting section.

In many of the shops and factories, the 50 work assigned to my improved routers and shapers has become so varied, and much of said work requires such accuracy in the handling of the machines, that some convenient means for supporting the machine, in a manner to permit universal movement thereof, have become imperative. I am aware that

universally operable brackets have been employed for similar uses heretofore, but none of these have proven satisfactory supports for my routers, for the reason that they lack 60 certain facilities for adjusting, as well as for locking, the adjacent members to each other, such as must be provided in order to effect many of the different kinds of work required of machines of the class, as herein 65 shown and described. Furthermore, in addition to the universal features, common to several of the older extensible supporting devices, it is necessary to provide means for adjusting and setting the machines, not only 70 for predetermining accurately the depth of the cuts, but also many different angles at which the routing or shaping tools must be operated. To this end, I have devised a novel universally operable bracket, which 75 will now be described:

In the drawing, 2 represents a pedestal or standard having a relatively broad base 2', for rigidly securing the same to a work bench or table, as 2''. The body of the pedestal is preferably threaded throughout its 80 length, as at 2''. 3 represents a pair of adjusting nuts, which are carried by the pedestal, and may be operated separately or jointly, for adjusting parts carried by the pedestal. 85 When the nuts 3 are tightened against each other they become locked against accidental movement on the pedestal.

4 represents a routing or shaping machine, comprising a high-speed electric motor 4', which is operatively enclosed in a 90 stationary cylindrical casing 4''. The armature shaft 5 of the motor preferably extends beyond the opposite ends of the casing, as shown in Fig. 1. The motor may be driven 95 by current derived from any source, as through wires 4^c—4^d. The external surface of the motor casing is shown threaded, as at 4''. The lower end of shaft 5 is preferably threaded, and to this end may be attached 100 any suitable chuck as 5', which holds the routing tool, as 5''. The motor 4' is preferably adjustably held during the working periods, by means of a clamping member or holder, which comprises a split cylindrical 105 body 6, that may be internally threaded for adjustably receiving and supporting the motor. Adjacent the split, the body 6 is formed with similar spaced parallel lugs 6'—6'', the said lugs being perforated and one of the 110 perforations being threaded. The clamping of the holder to the motor is effected by a

knurled screw 6^b, in the usual manner. Diametrically opposite the clamping lugs, the body 6 is formed with an integral relatively broad wing 7, which is preferably disposed in the plane of the axis of the motor, the said wing being perforated at 7', for pivotally mounting the holder, and said wing is also formed with a crescent-shaped slot 7^a, concentric to the said pivot opening. Beyond and substantially concentric to the slot 7^a the wing is fitted with segmental scale 7^b denoting degrees, said scale preferably reading from zero to about 45 degrees in opposite directions. The scale 7^b is employed for accurately tilting or inclining the motor and tool 7^a at different angles relatively to the adjacent supporting parts, as shown in Fig. 3.

The routing machine 4 is supported and adapted for universal movements over the work, as A, by a bracket, as 8, the said bracket comprising a number of sections, which are preferably pivotally joined to each other end to end, and the remote sections of the bracket are respectively connected to the pedestal 2 and the motor-holder 6. The first section of the bracket comprises an irregularly-shaped body 9, the latter being formed with a hollow cylindrical portion 9', which is split at one end, as at 9^a, the portion 9' having a smooth bore for slidably receiving the threaded portion of the pedestal 2, and being adapted to be clamped to the pedestal, by means of a hand-screw 9^b, that engages perforated clamping lugs 9^c, which are disposed at the opposite sides of the split. The opposite end of the section 9 is formed with a yoke 9^d, the arms of which are correspondingly perforated to receive a bolt 9^e, and below the yoke, the body 9' is formed with a radial boss or abutment 9^f.

The second section, of the bracket comprises a body 10, having at one end a perforated lug or ear 10', which is received in the yoke 9^d of section 9, and is held pivotally in place, by the bolt 9^e. Below the lug 10' the body 10 is fitted with nuts 10^a, which are arranged to frictionally engage the boss 9^f, and are employed for adjusting the section 10 in a vertical plane relatively to the section 9. Ordinarily the contact between the nuts 10^a and the boss is maintained by gravity. The opposite or forward end of section 10 is bifurcated, and the arms of the fork are correspondingly perforated to receive a bolt 10^b. The lower arm 10^c of the fork has a threaded perforation, to receive a clamping-screw 10^d.

The third section, comprises a similar body 12, one end 12' of which is disposed in the fork of the member 10, the said end being transversely bored to receive the bolt 10^b upon which the said section pivots. The bottom portion of the end 12' is formed with an integral disc 12^a, which normally bears

upon the inner face of arm 10^c of the member 10; the said disc being provided with a circular slot 12^b, through which the screw 10^c is inserted and plays, and by means of which the section 12 may be held in various adjusted positions relatively to the section 10, as shown in Fig. 2. The forward end of the section 12 is similarly forked, and the arms of the said fork are also perforated to receive a pivot bolt 12^d, the lower arm 12^e of the said fork being provided with a threaded perforation, to receive a clamping-screw 12^f.

The fourth section of the bracket comprises two members 13 and 14, which are preferably swivelled together for independent movement relatively to each other. The member 13 comprises a substantially cylindrical body having an enlarged vertically perforated head 13', which is received in the yoke of section 12, and is pivotally held in place by the bolt 12^d. The bottom portion of the head 13' is formed with a similar disc 13^a, the latter having a circular slot 13^b arranged concentric to the pivot 12^d, which receives the clamping screw 12^f, by which the parts may be locked in different adjusted positions, as shown in Fig. 2. The forward end of member 13 is bored out axially, as at 13^c, the said portion being split, as at 13^d, and being formed with clamping-lugs 13^e, the clamping of said parts being effected by a screw 13^f. In order to render the said clamping more effective, the split portion of the barrel is preferably formed with a transverse kerf 13^g, the latter being disposed between the lugs 13^e and the pivot 12^d. The member 14 is formed at one end with a reduced round portion 14', which pivots in the socket 13^c, and affords a desirable swivel action of said parts. The opposite end of the member 14 is flattened, and is arranged to directly support the wing 7, to which the said member is pivoted, by the pin 7^b, which passes through a perforation 14^a. Intermediate its ends the body 14 is provided with a threaded perforation to receive a clamping screw 14^c, which plays in the slot 7^a of the wing, and by means of which the motor may be held at different angles relatively to the axis of the member 14, as may be understood, by comparing Fig. 3 with Figs. 1 and 2. The router 4 may also be rotated together with the member 14 on the swivel 14'-13^c, as shown by the dotted lines 4^x in Fig. 2.

Having thus described my invention, what I claim, is—

1. In combination with a pedestal, a bracket member mounted on the pedestal, means for adjustably supporting the member on the pedestal, a boss carried by the member, a second bracket member pivoted to the first member, an adjustable element 130

carried by the second member and engageable with the boss so as to hold the second member in different pivoted positions relative to the first member, a motor having a peripherally threaded casing and having a router on its armature shaft, a cylindrical internally threaded member threadedly receiving the motor therein, and having a radial wing, a member having an axial socket, means to connect said last named member to the second bracket member, a member having a circular stem received in said socket and having a flat part, means to pivotally connect the wing of the cylindrical member to said flat part, and means connected to the wing and to said flat part for enabling the motor to be adjusted about said last named pivot.

2. In combination with a pedestal, a bracket member mounted on the pedestal, a second bracket member pivoted to the first member, adjustable means to hold the second bracket member in different pivotal

positions, a motor carrying member having a radial wing, a member having an axial socket, means to connect said last named member to the second bracket member, a member having a stem received in the socket and having a flattened part engaging the wing, and means to adjustably connect the wing and flattened part.

3. In combination with a pedestal, a bracket member mounted on the pedestal, a second bracket member pivoted to the first member, adjustable means to hold the second bracket member in different pivotal positions, a motor carrying member, means to mount said motor carrying member for rotary movement in a vertical plane, means to pivotally connect said motor carrying frame to said mounting means for pivotal movement in a plane at right angles to the first plane, and means to hold the motor carrying frame in adjusted positions.

In testimony whereof I affix my signature.
RAY L. CARTER.
